HYPODERMIC NEEDLE RACK

Loren Wallin, Wadesboro, N. C.

Application May 16, 1942, Serial No. 443,241

6 Claims. (Cl. 211—69)

This invention relates to a rack for hypodermic needles having novel and useful features hereinafter set forth.

It is a well known fact that hypodermic needles should be sterilized before using. It is equally important that the sterilized needles be supported in a manner so that the same may be attached or detached, to or from a hypodermic syringe without being touched by the hand or being otherwise contaminated.

Furthermore, when a large number of needles are being used, it is desirable to have the needles supported in such a position so that any moisture will readily drain therefrom and so that the operator can most conveniently attach and detach the needles to and from the syringe.

It is therefore an object of this invention to provide a hypodermic needle rack capable of supporting the needles in a convenient and accessible position for the operator, and at the same time maintaining the needles in a position which will afford the necessary drainage for the needles and for the pockets holding the heads of the needles. The specific structure of the needle rack or support comprises a pair of substantially parallel bars which are supported by end frames. The top side of each bar has a plurality of inwardly and downwardly inclined notches therein which conform to the shape of a hypodermic needle butt.

The ends of the notches are restricted so that when a needle is placed in the notch, it will be held in an inclined position thereby presenting the upper end of the needle butt in a more convenient and accessible position to the operator. As a means for permitting the moisture to drain from the notch holding a needle butt, a groove is provided in the lower end of each inclined notch.

It is another object of this invention to provide a hypodermic needle rack of the class described in which the inclined notches in one bar are staggered with relation to the notches in the other bar, thereby providing means for holding the overlapping lower ends of adjacent needles in spaced relation to each other, and yet close enough together to have a compact assembly. By providing a structure of this type the points of the needles are held between, and somewhat below, the two parallel bars, and therefore the bars protect the points from damage and thus insure efficiency and prolonged life of the needles.

It is another object of this invention to provide a needle rack as above described in com-

bination with a bail for handling the same, thereby making a portable unit. The rack may be carried on a tray or by hand from the sterilizing room to any part of the building, such as the clinic room without contaminating the needles or rack.

Some of the objects of the invention having been stated other objects will appear as the description proceeds when taken in connection with the accompanying drawing in which:

Figure 1 is an isometric view of my improved needle rack;

Figure 2 is a transverse vertical sectional view taken along the line 2—2 in Figure 1 and showing the present device used in association with a hypodermic needle syringe;

Figure 3 is a fragmentary plan view of one end of the needle rack showing the relative positions of the needle shanks in dotted lines;

Figure 4 is a detailed sectional view taken along the line 4—4 in Figure 2, but omitting the needles;

Figure 5 is a fragmentary view taken along the line 5—5 in Figure 2, but omitting portions of the needle and attached syringe;

Figure 6 is an isometric view of one of the needles which is adapted to fit in the needle rack;

Figure 7 is an enlarged sectional view showing a slightly modified form of support for a different type of hypodermic needle;

Figure 8 is an isometric view of the type of needle shown in Figure 7.

Referring more particularly to the drawing, the numerals 10 denote suitable end frames, each of which has inwardly inclined shoulders 11 on the upper ends thereof. In other words, there are a pair of inwardly inclined shoulders associated with each end frame. These shoulders are adapted to support a pair of spaced parallel bars 12 which are adapted to be secured thereto by any suitable means such as screws 14. Except for the fact that the pockets in one of the bars 12 are staggered with relation to pockets in the other bar, the structure of the two bars is identical. Therefore a description will be made of one of the pockets in one bar 12 and like reference characters will be given to the pockets in the associated parallel bar.

The pockets in each of the bars are broadly designated by the reference characters 16. It can be seen by observing the drawings that the shape of the pockets is made to conform to the butts of a hypodermic needle 17 such as illus-

trated in Figure 6. This needle has a substantially square butt 18 in which a bore 19 is provided. This bore 19 is of such shape and size as to receive the orifice projection 20 on the lower end of syringe 21 (see Figure 2). The butt 18 of the needle fits into the enlarged pocket or cavity portion 22 in the manner shown in Figure 2 and the lower and upper ends of the cavity 22 are restricted as at 24 and 25, thereby confining the butt within the pocket 16. When the butt 18 of the needle is positioned within the pocket 16, the projecting orifice 20 of the syringe may be easily inserted or removed from bore 19 because the restricted end portions 24 and 25 hold the needle in position.

The ends of cavity 22 indicated by reference characters 24 and 25, are open so as to permit easy removal of the needle from the pockets 16.

In order to provide for drainage of the pocket 16, a small groove 27 is provided in the lower end of pocket 16. This groove provides a means whereby liquid which drains from the butt 18 may flow from the pocket.

Another very important advantage in the disclosed structure is the inclination of the bars 12, as afforded by the inclined shoulders 11. When the needles are placed in the pockets 16, the pointed ends thereof are held in a downwardly inclined position. Furthermore, the needle shanks in many instances will overlap each other as shown in Figures 2 and 3. When in this inclined position, the opening 19 in the needle butt is more accessible to the operator when attaching to or detaching syringe 21 from the needle butt 18 than would be the case should the needle be in a horizontal position. This inclined position also makes drainage more easily accomplished. It also results in preventing slippage of the rack when a needle is being attached to a syringe.

In order to make the assembly portable, a suitable bail 30 is provided. This bail 30 has a loop 31 near its upper central portion and also has suitable pivots 33 which are secured to the upper central portion of the end frames 10. Normally when the rack is in the position to be used, the upper portion of the bail 30 rests across the upper open ends of the pockets 16.

In the actual operation of the device, all of the pockets in the needle rack are usually filled with the exception of one and this is permitted to remain vacant so that the needle which is attached to the syringe 21 may be deposited therein after use. This leaves a vacant notch or pocket between the used and unused needles. The operator uses one needle at the time and then replaces it in a pocket until the entire number of needles from one bar 12 are used. Then the bail 30 is rotated over on top of this used bar and then the same operation is repeated for the oppositely disposed parallel bar 12.

Figures 7 and 8 show a slightly modified form of structure which is employed for accommodating a different type of hypodermic needle. This structure comprises a bar 12a which bar has a notch 38 near the upper end thereof of suitable size and shape to accommodate a restricted collar portion 39 of the hypodermic needle broadly designated by the reference character 40. Adjacent the upper end of the collar 39 is a flange 42 which fits on the outer and upper portion of the bar 12a. The lower portion of the notch 38 is shouldered and adapted to abut the butt 43 of the needle 40. The butts rest in an enlarged pocket portion 44 which is directly below

notch 38 and the lower portion of this enlarged cavity 44 has a groove 45 communicating therewith which affords the necessary drainage for the cavity. If desired another shoulder 46 may be provided adjacent the lower edge of the inclined butt 43, but under ordinary circumstances this shoulder performs no particular function unless it would be necessary to make the racks so as to accommodate both the needles shown in Figure 6 and Figure 8. It is seen that the butt of needle 40 has a bore 48 therein which is adapted to receive orifice projection 20 of the hypodermic syringe 21. In this modified form of the invention the open ends of the hole 48 project to the exterior of the bar 12a whereas in the preceding form the uppermost end of the opening 19 is disposed below the outer confines of socket 16. In both cases however the hypodermic needles are held in an inclined and overlapping staggered position to each other so as to protect the points of the needles.

It is of course understood that the shape of the pockets can be varied to fit the butts of any particular needle being used.

In the drawing and specification, there has been set forth a preferred embodiment of the invention, and although specific terms are employed, they are used in a generic and descriptive sense only and not for purposes of limitation, the scope of the invention being defined in the claims.

I claim.

1. A support for hypodermic needles having an enlarged butt, comprising a framework including a pair of substantially parallel bars, each of said bars having a plurality of spaced transversely extending pockets therein, the longitudinal axes of which pockets are inclined with respect to the horizontal, each of said pockets being adapted to hold a needle butt in an inclined position, each of said pockets having a lower end wall provided with an opening for permitting liquid to drain from each of said pockets.

2. A support for hypodermic needles having a shank and an enlarged butt, comprising a framework including a pair of substantially parallel bars, each of said bars having a plurality of spaced pockets therein, the ends of the pockets being open and at least one end being restricted to a degree that the butt of a needle will not pass therethrough, said pockets in one bar being staggered relative to the pockets in the other bar, each of said pockets having a passageway in its lowermost portion to permit liquid to drain from each of said pockets.

3. In a support for hypodermic needles, a member having a plurality of transversely disposed pockets therein the longitudinal axis of which pockets are inclined with respect to the horizontal, means for supporting the member a substantial distance above a table top, each pocket having a pair of sidewalls and upper and lower end walls, the butt of a hypodermic needle being adapted to be disposed between the sidewalls, the upper end wall having a notch therein in which the upper restricted end of the butt is adapted to rest, the lower end wall also having a notch therein in which the lower restricted end of the butt is adapted to rest.

4. A support for hypodermic needles provided with butts having their upper and lower ends restricted, comprising a stand provided with a pair of horizontally disposed spaced bars, said bars having a plurality of transversely disposed pockets on their upper surfaces whose longitudinal axes are inclined inwardly and downwardly

towards each other, the ends of the pockets having notches therein for reception of the restricted ends of the butts of the needles.

5. A support for hypodermic needles provided with butts having their upper and lower ends restricted, comprising a stand provided with a pair of horizontally disposed spaced bars, said bars having a plurality of transversely disposed pockets on their upper surfaces whose longitudinal axes are inclined inwardly and downwardly towards each other, the ends of the pockets having notches therein for reception of the restricted ends of the butts of the needles, and a carrying bail pivoted at each end of the support, and between the bars, and having a radius of such length that when swung to one side the bail will rest on and above the pockets of one bar to

thereby indicate that the needles in the other bar are next in order to be used.

6. A support for holding hypodermic needles provided with butts which are substantially of greater cross-section than that of the needle portion, comprising a member having a plurality of pockets having side-walls and end walls for receiving the butts of the needle, the longitudinal axes of the pockets being inclined relative to the horizontal so that the liquid in used needles will drain from the needle, the upper and lower end walls of the pockets being cut away sufficiently for the lower end of the butt to be disposed in the cut-away portion of the lower end wall and whereby the upper end of the butt is rendered accessible for insertion of a syringe thereto.

LOREN WALLIN.
